LINK CHAIN FOR A BRACELET OR SIMILAR
ARTICLE

Michael Chernow, New York, N. Y.

Application April 15, 1950, Serial No. 9,248

Term of patent 14 years

(Cl. D45—16)

To all whom it may concern:

Be it known that I, Michael Chernow, a citizen of the United States and residing at New York, in the county of New York and State of New York, have invented a new, original, and ornamental Design for a Link Chain for a Bracelet or Similar Article, of which the following is a specification, reference being had to the accompanying drawing, forming part thereof, and in which

Fig. 1 is a perspective view of a link chain for a bracelet or similar article, showing my new design,

Figs. 2 and 3 are top plan and side elevational views respectively of a portion of the link chain, and

Fig. 4 is an end elevational view thereof.

I claim:

The ornamental design for a link chain for a bracelet or similar article, substantially as shown.

MICHAEL CHERNOW.
